UNITED STATES PATENT OFFICE

LOWELL C. BLOMSTROM, OF DETROIT, MICHIGAN, ASSIGNOR TO FEDERAL MOGUL CORPORATION, OF DETROIT, MICHIGAN, A CORPORATION OF MICHIGAN

PROCESS OF FORMING HALF BEARING SHELLS AND RESULTANT ARTICLE

Application filed September 10, 1929. Serial No. 304,984.

This invention relates to an improved process for forming a half bearing shell and to the resultant article as such, and has for its object an improved and markedly economical method of forming to the shape required the semi-cylindrical bearing shell, which, when thereafter babbitted or otherwise treated for the production of a bearing surface, may be, and today is, largely used, in cooperation with a companion shell, in gas engines and similar bearing work.

Heretofore it has been the practice to form such a bearing shell, whether of steel, bronze, or other equivalent material by casting or otherwise producing a complete cylindrical blank with appropriate marginal flanges, and then separate it into halves and subject it to other process steps not necessary here to discuss, before the shell could be considered as ready for machining or babbetting. Some few relatively unsatisfactory articles have also been produced by longitudinally dishing or troughing a piece of metal into cross-sectionally semi-circular shape, and thereafter forming outwardly extending flanges from its convex side by grinding away or otherwise removing a sufficient amount of metal from its convex surface so as to leave marginal flanges. Both as regards the expense and in some instances as regards the characteristics of the completed article, both of these methods have been found open to objection, and it is the purpose of this invention to obviate this fault as regards expense, and, as partially preliminary thereto, to reduce the number of the machining operations involved. A very appreciable saving in material may also be thus effected.

In the drawings:

Figure 1 is a perspective of a plane or flat oblong blank of relatively malleable metal, such as steel or bronze, which forms the starting point in the production of the improved article herein dealt with.

Figure 2 is a perspective showing the second step in the manufacturing operation, to wit, the flanging of the marginal edges of the blank.

Figure 3 is a similar perspective showing the channeling or slight grooving of the

blank immediately adjacent and interiorly of each lateral flanges.

Figure 4 is a perspective of the half-bearing shell in its completed form.

Figure 5 is an elevational view partly in section showing the position of the blank when its fabrication has reached the stage shown in Figure 3, upon a suitable forming die, and with the correspondingly contoured entering die positioned thereabove.

Figure 6 is a similar sectional elevational view showing the die and its included blank after the descent of the superiorly positioned entering die.

Figure 7 is a partly sectional elevational view, taken at right angles to the position shown in Figure 5, bringing out further the action of the entering die relatively to the blank before its deformation.

Having decided upon the gauge or desired wall thickness of the half-bearing in its completed form, I provide a suitable number of blanks, initially of relatively soft metallurgical character and of carefully predetermined dimensions, the length being that of the intended interior measurement of the completed blank as shown in Figure 4, taken circularly thereof through its middle portion. This flat blank A I first subject to die press action so as to form marginal flanges B along the long sides thereof. The next step in the process consists in machining grooves C in each marginal edge of the surface D which remains after the turning up of the flanges B, thus forming small troughs 85 immediately adjacent and within each flange. I then position the blank as thus altered and fabricated, upon the lower or receiving die E, which is provided with active concave surfaces F and G of similar curvature to the intended outer curvature of the completed half bearings, one end being positioned against a stop or pin P to assure its correct positioning thereover. I then bring down thereupon with adequate force the entering die Q, which is provided with a rounded convex surface of the same curvature as that of the inner face of the half bearing which it is desired to make. This effects the bending of

both the intermediate web portion D of the

blank and of the flanges B to the curvature desired, and the now formed blank may be ejected from the receiving die E in which it is naturally quite firmly seated, by means of 5 the knock-out punch J. The provision in the ultimate outer or convex surface of the half bearing of the marginal grooves C effects an undercutting contouring of that face of the bearing, and makes it a comparatively easy 10 matter to effect a finishing machining, as by grinding, of the surface, preparatory to the further and finishing treatment of the half bearing. This is brought out with particular clearness in Figures 4 and 6. However, 15 if the bending up of the flanges B can be made sharply angular enough as regards the lines of meeting of their interior surfaces with the intermediate surface D, so as to in itself give an undercut effect to these angles 20 even after the blank has been bent to semicircular form, this described second step of the process may be omitted.

Unless a very ductile grade of metal is used, there is a tendency on the part of the 25 half bearing when completed for its marginal flanges, though satisfactorily bent near the ends L, to bulge somewhat near its center portion as M. To counteract this, I very slightly taper the sides of the receiving die E 30 from top to bottom as indicated at N, in Figure 5, so that when the circularly deforming movement of the blank is at an end and the end portions of the flanges as L are bent to just the degree required, the intermediate 35 portion of the flanges, as M, will be bent slightly more than required, so that when the half-bearing is released and ejected from the die, the tendency of the central portion M of the flanges to spring back somewhat can be 40 relied upon to bulge them out once more to just the proper degree and so as to be in ultimate alignment with end portions L. Actually this variance or tapering in the bearing of the receiving die E, which is indicated in 45 exaggerated form at N, need be but a very few thousandths of an inch, and it is not always necessary to resort to this, a receiving die member with parallel rather than inclined surfaces being adequate.

50 Dependent upon the initial degree of hardness of the steel, bronze or other metal used, and upon the desired rigidity of the completed half bearing shell, it may be desirable, after the half bearing shell has been fully 55 formed as above described, to harden the component metal in any one of several well known ways which it is not necessary here to discuss.

Having described my invention, what I 60 claim is:

1. The process of forming a half-bearing shell, which consists in laterally flanging a plain blank of selected dimensions, forming grooves lengthwise of those lateral edges 65 thereof next inside of the flanges as formed,

positioning the flanged and machined blank over a semicircularly concaved receiving die, and subjecting the blank as thus positioned to the impact of a correspondingly contoured entering die. 70

2. The process of forming a half-bearing shell, consisting in forming upstanding flanges from the lateral edges of a flat blank of selected dimensions, forming grooves along the edges of that face thereof then flanked by said flanges, and subjecting the blank as thus modified to the semicircularly forming impact of a pair of cooperating die members. 75

3. The process of forming a half-bearing shell, consisting in forming into upstanding flanges the lateral edges of a flat blank, grooving that surface thereof immediately adjacent the intersection of the formed flanged edges with the intermediate plane surface thereof, and subjecting the thus contoured blank to the semicircularly bending action of a pair of cooperating and complementarily formed die members. 80

4. The process of forming a half-bearing shell, which consists in laterally flanging a flat blank, forming relatively narrow grooves in the then concaved face thereof along the lines of union of the flanges and the intermediate web, and subjecting the blank as thus contoured to the semicircularly bending action of a pair of complementarily formed die members. 90

5. The process of forming a half-bearing shell, consisting in bending the lateral edges of an initially flat blank into sharply right angular relation to the intermediate surface of the blank flanked by them, positioning the blank over a concaved forming die having slightly tapered side walls, whereby the intermediate portions of the flanges are in-bent slightly in excess of the degree ultimately desired while confined within the die recess, and subjecting the blank as thus positioned to the bending pressure of a correspondingly curved entering die. 100

In testimony whereof I sign this specification.
